W. R. SMITH.
CLOUD CRUSHER AND PULVERIZER.
APPLICATION FILED FEB. 21, 1916.

Patented July 11, 1916.

Fig. 1.

UNITED STATES PATENT OFFICE.

WALTER RAMSEY SMITH, OF FORREST CITY, ARKANSAS.

CLOD CRUSHER AND PULVERIZER.

1,190,601.

Specification of Letters Patent. Patented July 11, 1916.

Application filed February 21, 1916. Serial No. 73,654.

To all whom it may concern:

Be it known that I, WALTER RAMSEY SMITH, a citizen of the United States, residing at Forrest City, in the county of St. Francis and State of Arkansas, have invented certain new and useful Improvements in Clod Crushers and Pulverizers, of which the following is a specification, reference being had therein to the accompanying drawing.

10 This invention relates to certain new and useful improvements in clod crushers and pulverizers; the object being to provide a crushing roll formed of a series of wheels having pyramidal teeth for breaking up the clods; these teeth being arranged in staggered relation in respect to one another on the complete crushing roll in order to form spirally arranged rows of teeth which act upon the clods in such a manner as to thoroughly crush the same.

15 Another object of my invention is to provide a crusher and pulverizer in which the wheels constituting the crushing roll are secured together by bars so as to cause the 20 wheels to rotate in unison.

25 Another object of my invention is to provide a clod crusher and pulverizer in which a crushing roll is employed and a harrow, so that the clods after being crushed and 30 broken up by the crushing roll, will be pulverized by the harrow.

35 Another object of my invention is to provide a clod crusher and pulverizer which is exceedingly simple and cheap in construction; the wheels constituting the crushing roll being formed identical, but being secured together in staggered arrangement so as to form the complete crushing roll with 40 spirally arranged teeth.

45 Other and further objects and advantages of the invention will be hereinafter set forth and the novel features thereof defined by the appended claims.

50 In the drawing—Figure 1, is a side elevation of my improved construction of clod crusher and pulverizer; Fig. 2, is a section taken on the line 2—2 of Fig. 1; and Fig. 3, is a detail plan view of a portion of the complete crushing roll showing the manner of 55 arranging the independent wheels to produce a crushing roll with spirally arranged teeth.

Like numerals of reference refer to like parts in the several figures of the drawing.

55 In carrying out my invention, I employ a frame 1 which is provided with depending

converging arms 2 terminating in split bearings 3 in which is arranged an axle 4 secured in position therein by a washer and cotter pin 5. The frame 1 is provided with a tongue socket 6 in which a tongue 7 is mounted carrying the ordinary form of double-tree 8 to which the draft-animals can be connected in the ordinary manner. Mounted on the frame 1 is a box 9 in which is adapted to be placed, stones or any other suitable weights. Connected to the depending arms 2 are the arms of a spring-seat support 10 carrying a seat 11.

60 Mounted on each end of the axle 3 is a draft bar 12 connected to a harrow 13 by links 14, said harrow being arranged under the seat 11 and the particular construction of harrow forms no part of this invention. Arranged on the axle 3 between the depending 75 converging arms 2 of the frame 1 is a crushing roll formed of a series of wheels 15, the tread of each wheel being provided with pyramidal-shaped teeth 16, each tooth having a base substantially diamond-shaped, 80 the point of each tooth extending laterally beyond the tread of the wheel as shown in Figs. 2 and 3. The wheels 15 are arranged on the axle 3 so that the projecting points of the teeth extend into the space between 85 the spaced teeth of the adjacent wheel and it will be seen that when the series of wheels is assembled on the axle, as shown in Figs. 2 and 3, the edges of the base of the teeth are parallel with one another so that the 90 teeth extend around the circumference of the complete crushing roll in a spiral manner in both directions. The wheels 15 are each formed exactly alike, the tread of each wheel having spaced teeth arranged 95 thereon and in assembling these wheels on the axle, they are arranged as shown in Fig. 3, which brings the spokes of the wheels into alinement. The spokes of the wheels are adapted to be connected by a bar 17 extending 100 through the series of wheels having clips 18 and it will be noticed that I have employed two bars, as when the wheels are arranged so as to bring the diamond-shaped teeth of every other wheel in longitudinal 105 alinement, the spokes of every other wheel will also be in alinement and the wheels can be securely fixed together by the use of two bars 17 so that a complete crushing roll is formed. By the use of pyramidal teeth on 110

a series of wheels arranged to form a complete crushing roll, the spaces between said

teeth form a recess having inclined walls so that when a clod is struck, the apex of said pyramids break and thoroughly crush the same.

5 From the foregoing description, it will be seen that I have provided a novel form of crushing roll for a clod crusher and pulverizer which is formed of a series of wheels each wheel having a series of teeth on 10 the tread thereof, which when arranged upon a common axis and united to rotate in unison, form a crushing roll with spirally arranged teeth so as to thoroughly break up the clods.

15 I claim:

1. A clod crusher and pulverizer having a crushing roll formed of a series of wheels, each wheel being provided with pyramidal teeth of a greater width than the tread of 20 the wheel adapted to rest on the tread of the adjacent wheels.

2. A clod crusher and pulverizer comprising an axle, a series of wheels mounted on said axle, each wheel being provided with a 25 series of pyramidal teeth having overhanging portions, and means for connecting said wheels together with the overhanging portions of the teeth resting on the tread of the adjacent wheels.

30 3. A clod crusher and pulverizer comprising an axle, a series of wheels arranged upon said axle, said wheels being provided with overhanging pyramidal teeth, the base of each tooth being substantially diamond-shaped, and means for locking said wheels together with the teeth of the adjacent 35 wheels out of alinement, with the edges of the teeth arranged in spiral manner.

4. In a clod crusher and pulverizer, the

combination with an axle, of a series of 40 wheels arranged upon said axle, each wheel being provided with a series of pyramidal teeth having overhanging portions, and means for locking said wheels together with 45 said teeth arranged in spiral manner with the overhanging portions of said teeth resting on the tread of the adjacent wheels.

5. A clod crusher and pulverizer, having a crushing roll formed of a series of wheels, each wheel having pyramidal teeth provided 50 with overhanging portions resting on the tread of the adjacent wheels, and means for locking said wheels together with the teeth of said wheels arranged in staggered relation.

6. A clod crusher and pulverizer, comprising an axle, a series of wheels mounted upon said axle, each wheel being provided with a series of pyramidal teeth having overhanging portions, said wheels being arranged 60 upon said axle with the teeth thereof overlapping the adjacent wheels, and bars extending through the spokes of said wheels having clips for securing said bars to said spokes.

65 7. A clod crusher, having a crushing roll formed of a series of wheels mounted upon an axle, means for securing said wheels together, and pyramidal teeth formed on the tread of said wheels having overhanging portions arranged over the tread of the adjacent wheel.

In testimony whereof I hereunto affix my signature in the presence of two witnesses.

WALTER RAMSEY SMITH.

Witnesses:

C. W. STEWART,
C. L. SMITH.
